UNITED STATES PATENT OFFICE

2,042,568

REFRIGERATION SYSTEM

Clarence D. Tuska, Philadelphia, Pa., assignor to
 Atwater Kent Manufacturing Company, Philadelphia, Pa., a corporation of Pennsylvania

Application September 29, 1934, Serial No. 746,104

5 Claims. (Cl. 62—4)

My invention relates to refrigeration systems. More specifically I have devised means to automatically defrost the evaporator of a refrigeration system.

One of the objects of my invention is to automatically defrost the evaporator of a refrigeration system. Another object is to automatically restore the normal cycling of the system after defrosting. A still further object is to restrict the automatic defrosting means to operation during the hours when it will least interfere with normal use of the refrigerator.

Figure 1 represents an elevation view, partly in section, of a conventional domestic refrigeration system to which my invention has been added.

Figure 2 is the top plan view, partly in section, of the evaporator shown in Figure 1.

Figure 3 is an elevation view, partly in section, of an alternate method of employing my invention.

In Figure 1, 1 represents a refrigerator box. External to box 1 is the refrigeration mechanism. 2 represents an electric motor. Drive wheel 3 of the motor is coupled by belt 4 to a driven wheel 5 which is part of compressor 6. The chamber of the compressor is connected to the condenser 7. The condenser in turn connects to the storage tank 8. The tank connects to expansion valve 9 and from the expansion valve 9 the refrigerated liquid normally goes to the evaporator 10. The return from the evaporator 10 goes to the intake 11 of compressor 6.

Instead of coupling directly from the expansion valve 9 to evaporator 10, I interpose the defrosting mechanism of my invention. On a suitable support 12 are mounted two tubes; one, a tube connected to the expansion valve 9, the other, a tube 13 connected with the evaporator. On the free ends of each of these tubes are connected expansible couplings or sylphons 14 and 15. The purpose of these couplings is to provide a maximum flexibility. The two couplings 14 and 15 are connected together by tubing 16.

On the end of 16 is suitably mounted a mercury contact device. The contact device may be a glass vessel 17. Within 17 are mounted two contacts, 18 and 19. A pool of mercury 20 connects contacts 18 and 19 as long as 16 remains in a substantially horizontal position. When the refrigeration system is in operation, frost and ice will gradually collect on 16 and 10. The presence of such a coating of frost and ice is objectionable. The coating acts as an insulator and reduces the efficiency of the evaporator. Furthermore, the presence of ice may make it difficult to remove

the ice freezing trays 21 which are generally located within the evaporator.

The collection of an objectionable coating of ice on 16 will upset the balance of 16 because of the weight of the ice. The free end of 16 will move downwardly. As 16 departs from a horizontal position, the contact between 18 and 19 will be opened. The connection between 18 and 19 is in series with power source 22. With the power source thus disconnected, the refrigeration system will cease operation. The frost and ice will gradually melt from the surface of 16 and 10. This removes the load on 16 and permits it to return to its normal position. In the event that there is insufficient spring in 14 and 15 to restore 16 to normal position, a supplemental and adjustable spring 23 may be mounted on support 24. The adjustment is represented as screw 25.

As soon as 16 is restored to horizontal position the motor circuit is completed and the refrigeration system is ready to resume operation. In the ordinary domestic system, a thermostatic control 26 is used to maintain the box within suitable temperature limits. The arrangement proposed does not affect the usual thermostatic control, except during defrosting.

It will be understood that the collection of frost and ice does not take place rapidly, but takes several hours or even days. Defrosting is also relatively slow. It may be objectionable to have the defrosting take place during the usual hours of access to the box. For example, the defrosting might start just when the user wants to freeze water, or desserts. In such cases a twenty-four hour electrically operated clock and switch 27 may be used to short circuit the device 17, except during the hours when the refrigerator box remains closed. This simply delays the operation of defrosting until certain convenient hours.

The expansive joints 14 and 15 are preferably of metal. Frost and ice might collect on these joints and prevent the proper operation of the defrosting mechanism. A suitable covering 28 of heat insulating material, such as wool or the like, covers the joints to prevent the collection of frost and ice.

In Figure 2 is illustrated a grille work of metallic wires or tubes 29 which may be used to add to the surface of 16 to permit a larger accumulation of ice to insure the unbalancing of 16. The maximum sensitivity of the defrosting device will depend upon the weight of 16, its associated movable parts and the flexibility of 14 and 15. The weight should be reduced as much as possible. Aluminum parts and tubing may be used to ad-

vantage. The longer the length of 14 and 15 the greater flexibility will result. The actual size and weight of the mechanism may be proportioned to the system in which it is to be employed. It may be made more or less sensitive without departing from the scope of my invention.

In Figure 3 an alternate arrangement is shown in which the flexible joint 14 connects to an evaporator 18 instead of forming a loop in the incoming refrigerator line. The tubing 18 in this case is dead ended at 30 and depends upon circulation of the refrigerant within itself. This alternate arrangement is desirable in that a single flexible joint 14 adds to the sensitivity of the defrosting device. In place of the the expansive joint or sylphon 14 a suitable spiral or helix of tubing may be used to provide flexibility.

Thus it will be seen that my invention provides means for automatically defrosting a refrigeration system. After defrosting, normal operation is automatically resumed. Means have also been provided to automatically delay the operation of the defrosting device until convenient hours.

I claim:

1. In a refrigeration system, a source of power for said system, an evaporator, an expansion valve, a connection between said expansion valve and said evaporator, means permitting movement of said connection, means to prevent the collection of ice on the first mentioned means, and means responsive to the movement of said connection to control the application of said power.

2. In a refrigeration system, an evaporator, a

flexible connection to said evaporator, means responsive to the flexing of said connection to control the application of power to said refrigeration system, and means comprising a time operated switch to delay the action of the last mentioned means.

3. In a refrigeration system, an evaporator, a flexible connection to said evaporator, means to prevent the collection of frost on said flexible connection, means responsive to the flexing of said connection to control the application of power to said refrigeration system, and means to delay the action of the last mentioned means.

4. In a refrigeration system, a source of power for said system, an evaporator, an expansion valve, a sylphon connected to the evaporator, a second sylphon connected to the expansion valve, a U shaped connection between the two sylphons, and means attached to the outer end of the U shaped connection responsive to movement of the connection to control the application of power to the refrigerator system.

5. In a refrigeration system, a source of power for said system, an evaporator, an expansion valve, a sylphon connected to the evaporator, a second sylphon connected to the expansion valve, a U shaped connection between the two sylphons, means for heat insulating each of the sylphons, and means attached to the outer end of the U shaped connection responsive to movement of the connection to control the application of power to the refrigerator system.

CLARENCE D. TUSKA.
